UNITED STATES PATENT OFFICE.

JACOB LOWE YOUNG, OF NEW YORK, N. Y.

METHOD AND APPARATUS FOR GRINDING SURFACES.

Application filed January 14, 1925. Serial No. 2,314.

This invention relates to the art of grinding surfaces and more particularly to the internal grinding of cylinders.

One of the objects of the invention is to provide a method and apparatus whereby the actual grinding of the surface may be done by a suitable grinding paste, such as carborundum paste.

A further object of the invention is to provide means for feeding the grinding paste between a grinding tool and the surface that is being ground as the grinding operation progresses.

In the drawings, Fig. 1 is a top plan view of the grinding apparatus partly in section showing a block of cylinders mounted thereon to be ground;

Fig. 2 a section taken approximately on the line 2—2 of Fig. 1;

Fig. 3 a detail view showing the manner of disconnecting the cylinders and grinding tools from the apparatus;

Fig. 4 a section through the apparatus taken on the line 4—4 of Fig. 1;

Fig. 5 a longitudinal section through one of the grinding tools;

Fig. 6 a detail section showing the paste feeding means;

Fig. 7 a transverse section on the line 7—7 of Fig. 5; and

Fig. 8 an end view of the grinding tool.

Referring to the parts by numerals 1 designates the supporting frame of the grinding apparatus. A drive shaft 2 extends across the top 3 of the frame adjacent one edge and is supported in bearings 4 mounted on the frame top. A plurality of worms 5 are keyed to the shaft along its length and are adapted to rotate a series of worm-wheels 6 keyed to a series of short tool-driving shafts 7. The shafts 7 are each supported to rotate within spaced bearings 8 mounted upon the frame top, and the number of said shafts corresponds to the number of cylinders to be ground simultaneously. In the drawings, the apparatus is shown as adapted to grind the four cylinders of a gas engine. The cylinder block B is mounted upon the top 3 of the frame in any suitable manner with its cylinders in a horizontal position and each centered with one of the tool driving shafts 7. Prior to placing the cylinder block in position, a grinding tool 9 is placed within each cylinder. These tools are cylindrical in form and each is divided longitudinally into semi-cylindrical halves 10 which

are adapted to be forced apart to expand the tool, as will be presently described. Each of the halves 10 is formed with inner and outer semi-cylindrical walls 11 and 12 respectively. These walls are spaced apart to provide an annular space 13 therebetween. The space 13 is confined at the ends of the tool halves by the end walls 14 and along the lines of separation of the tool halves by the longitudinally extending walls 15. A shaft 16 extends longitudinally through the center of each tool and has fixed to it a pair of spaced collars 17 and 18 which are located adjacent the opposite ends of the tool. The collar 17 is connected with both tool halves 10 at diametrically opposite points of the tool by means of outwardly extending links 19. Each link is pivoted at its inner end between a pair of pivot ears 20 on the collar 17 and is pivoted at its outer end between a pair of pivot ears 21 on the end walls 14 of the tool halves. The collar 18 is connected in precisely the same manner by means of links 19' to the opposite ends of the tool halves.

The links 19 and 19' are of the same length and are disposed parallel to each other to provide a toggle connection between the shaft 16 and the tool halves, whereby when the shaft is moved longitudinally in one direction relatively to the tool, the tool will be expanded equally throughout its length. Located between the inner walls of the tool halves are two pairs of tension springs 22 each of which is connected at one end to an inwardly extending guide tube 23 fixed to one of the halves and at its opposite end to a rod 24 fixed to the other tool half and adapted to telescope within the tube 23. These springs serve to automatically contract the tool when the expanding thrust upon the shaft 16 is relaxed. The shaft 16 extends beyond the collar 18 and is formed with a squared tapered end 25. The opposite end of the shaft extends beyond the collar 17 and is reduced to form a centering pin 26.

Extending outwardly from the end wall 14 of each of the tool halves 10 at the end adjacent the collar 18 is a tubular extension 27. Each of these tubes opens into the space 13 between the inner and outer walls of its respective tool half and is internally threaded throughout its length to receive a threaded plunger 28. An outwardly extending stem 29 of considerable length is fixed to the plunger and carries at its outer end a star

wheel 30. The plunger is adapted to be unscrewed by means of the star wheel and removed from the tube 27. The annular space 13 may then be charged through the tube 27 5 with a suitable grinding paste, such as carborundum paste. The outer walls 13 of the tool halves are formed with closely spaced openings 31 to provide the tool with a foraminous grinding face 32. The space 13 10 and the tube 27 are filled with the paste and when the plunger is reinserted in the tube and screwed inwardly, the paste will be forced by the pressure of the plunger out through the foraminous face of the tool. 15 A tool driving and abutment fork 33 is keyed to each tool-driving shaft 7 and the ends of said fork are bifurcated as at 34. These bifurcated ends are adapted to straddle the diametrically located pivot ears 21 20 upon the tool and to abut the end of the tool. This provides a separable driving connection between the shaft 7 and the tool. The fork 33 is centrally formed with a socket 35 in alignment with the center of shaft 27 and 25 adapted to receive the centering pin 26 of the tool.

A cross head 36 is located at the opposite end of the frame top 3 from the main drive shaft 2 and extends parallel to the said shaft. 30 This crosshead is slidable between guides 37 at its ends, mounted upon the top of the frame and is adapted to have a limited parallel movement toward or from the adjacent ends of the tools 10. This movement is given 35 to the crosshead by means of a lag screw 38 swiveled at its inner end to an upstanding ear 39 upon the crosshead and threaded through a sleeve 40 fixed to the frame 1, said screw being adapted to be turned by means 40 of a hand wheel 41. The crosshead 36 serves as a carrier and support for a bearing-supporting bar 42 mounted between guides 43 at its ends and adapted to be slid upon the crosshead toward and from the 45 tools. The bar 42 carries a series of tool centering thrust bearings 44 pivotally mounted in the bar and formed with squared sockets 45 in alignment with the sockets 35. The sockets 45 are adapted to receive the 50 squared ends 25 of the tool shafts 16 and center the tools within the cylinders to be ground.

When a block of cylinders is to be ground 55 the tools are first placed thereon and then the cylinder block and tools are placed upon the frame 1 with the bifurcated ends of the driving forks 33 engaging the pivot ears 21 of the tools and the centering pin 26 engaging in the socket 35 of the fork. A preliminary adjustment of the bearings 44 toward 60 the squared shaft ends 25 is then made by turning the hand wheel 41 and moving the crosshead 36 and the bar 42 toward the tools. The final adjustment of the centering and 65 thrust bearings 44 for the purpose of accu-

rately expanding the tools is made by means of a screw 46 formed with a knob 47 and threaded through a bracket 48 fixed to the center of the crosshead 36. The screw 46 is swiveled at its lower end to a downwardly tapered wedge 49. The opposite wedge faces of the wedge engage the beveled faces 50 of a pair of adjusting bars 51. The bars extend from the wedge toward the guided ends of the crosshead 36 and have their outer ends beveled as at 52. The ends of the bearing supporting bar 42 are formed rearwardly with beveled extensions 53. These extensions are adapted to be engaged by the beveled ends of the rods 51.

By forcing the wedge 49 downwardly by means of the screw 46, the bars 51 will be moved outwardly and its beveled ends will be forced against the beveled extensions 53 and give the bar 42 a forward parallel movement. The bearings 44 will be carried forward by bar 42 and exert a thrust upon the shafts 16 which, through the toggle links, will expand the tools. The forks 33 abutting against the ends of the tools prevent them from being moved longitudinally by the expanding thrust of the shaft 16. The socket 35 is sufficiently long to permit the reduced end of the shaft to slide therein when expanding the tool. In order to reduce the friction caused by the expanding thrust, the forks 33 and the bearings 44 at the opposite ends of the tools are shouldered and ball bearings 54 and 55 are interposed between the shouldered forks and the bearings 8 and between the shouldered bearings 44 and the bar 42 respectively. The adjustment bars 51 are guided by guide brackets 56 and connected to the bars 51 and to the innermost brackets are tension springs 57. These springs tend to retract the bars and hold them against the wedge when the wedge is drawn upwardly.

As previously described, before the grinding operation is started the tools are filled 110 with grinding paste. The actual grinding is done by this paste, and in order to feed the paste out through the foraminous grinding face of the tool as the grinding progresses, automatic feeding means are provided. Upon the upper edge of the bar 42 a shaft 58 is rockably mounted and has a number of collars 59 mounted thereon corresponding to the number of tools and carrying radially extending pins 60. These pins are adapted, by turning the shaft 58 through the means of a handle 61, to be swung into the path of movement of the star wheels 30. As the tools are rotated therefore through the main drive shaft 2, the shafts 7 and the forks 33 for the grinding of the cylinders, the points of the star wheels will engage the pins 60 and be turned slightly upon each rotation of the tools. The turning of the star wheels 115 will force the plungers 28 inwardly through 120 125 130

tubes 27 and press the grinding paste out through the foraminous grinding faces of the tools. The close spacing of the apertures in the grinding faces of the tools ensures an even distribution of the paste over the said faces and a uniform grinding of the cylinders by the paste. When it is desired to discontinue the paste feed, shaft 58 is rocked back to move the pins upwardly out of the path of the star wheels. A click spring 62 is adapted to engage either of a pair of spaced notches on one of the collars 59 and yieldingly hold the shaft and pins either in operative or in-operative position.

At the completion of the grinding operation the cross-head 36 is retracted by turning the hand wheel 41. The tools are then freed from the forks 33 as shown in Fig. 3 and the cylinder block and tools are free to be lifted from the apparatus.

It will, of course, be understood that the invention is not restricted to the internal grinding of cylinders but that it comprehends the grinding of surfaces of various forms either internal or external. It will be further understood that the invention is not restricted to moving the grinding tool toward the surface to be ground as the grinding progresses, as it is obvious that the grinding result may be accomplished by relative movement of either the surface or the tool.

What I claim is:

1. An apparatus for grinding surfaces, comprising a hollow rotatable grinding tool adapted to be filled with grinding paste, means for rotating the tool, and an automatic mechanical means carried by the grinding tool for maintaining a pressure on said paste to positively force it between the grinding face of the tool and the surface to be ground.

2. An apparatus for grinding surfaces, comprising a hollow rotatable grinding tool adapted to be filled with grinding paste, means for rotating the tool, and mechanical means operated by the said tool-rotating means to automatically maintain a pressure upon said paste and positively force it between the grinding face of the tool and the surface to be ground.

3. An apparatus for grinding surfaces, comprising a hollow rotatable grinding tool formed with a foraminous grinding face and adapted to be filled with grinding paste, and an automatic mechanical means carried by the grinding tool and operated by the rotation of said tool for maintaining a pressure upon the said paste to positively force it out through the foraminous face of the tool during the grinding operation.

4. An apparatus for grinding surfaces, comprising a hollow rotatable grinding tool formed with a foraminous grinding face and adapted to be filled with grinding paste, means to rotate said tool, and means op-

erated by the said tool-rotating means to automatically force said paste out through the foraminous face of the tool during the grinding operation.

5. An apparatus for grinding surfaces, comprising a hollow grinding tool formed with a foraminous grinding face and adapted to be filled with grinding paste, means to cause relative rotation between the tool and the surface to be ground, and an automatic mechanical means carried by the grinding tool for maintaining a pressure upon said paste to positively force it out through the foraminous face of the tool during the grinding operation.

6. An apparatus for grinding surfaces, comprising a hollow grinding tool formed with a foraminous grinding face and adapted to be filled with grinding paste, means to cause relative movement between the grinding tool and the surface to be ground, and an automatic mechanical means carried by the grinding tool and operated by the relative movement between the grinding tool and the surface to be ground for maintaining a pressure upon said paste to positively force it out through the foraminous face of the tool during the grinding operation.

7. An apparatus for simultaneously grinding a plurality of surfaces, comprising a plurality of grinding tools, means to cause simultaneous relative grinding movement between the tools and the said surfaces, and means operated by said movement-causing means to automatically feed grinding paste between the grinding faces of the tools and the surfaces to be ground.

8. An apparatus for simultaneously grinding a plurality of surfaces, comprising a plurality of hollow rotatable grinding tools formed with foraminous grinding faces and adapted to be filled with grinding paste, means to cause simultaneous relative rotation between the tools and said surfaces to be ground, and means operated by said rotation-causing means to automatically force the said paste out through the foraminous grinding faces of the tools.

9. An apparatus for simultaneously grinding a plurality of surfaces, comprising a plurality of grinding tools, means to cause simultaneous relative grinding movement between the tools and the surfaces to be ground, means to automatically and positively feed grinding paste under pressure between the grinding faces of the tools and said surfaces, and means to simultaneously and synchronously move the tools toward the said surfaces as the grinding progresses.

10. An apparatus for grinding concave surfaces, comprising an expandible grinding tool, means to cause relative rotation between the grinding tool and the surface to be ground, means operated by said rotation-causing means to automatically feed grind-

ing paste between the grinding face of the tool and said surface, and means to expand the tool as the grinding progresses.

11. An apparatus for internally grinding a plurality of cylinders simultaneously comprising a plurality of rotatable hollow grinding tools each formed with a foraminous grinding face and adapted to be filled with grinding paste, means to simultaneously 10 rotate said tools, means to positively force said paste out through the foraminous faces of the tools, and means to expand the tools simultaneously and equally as the grinding progresses.

12. An apparatus for internally grinding a plurality of cylinders simultaneously, comprising a plurality of rotatable hollow grinding tools each formed with a foraminous grinding face and adapted to be filled 20 with grinding paste, means to simultaneously rotate said tools, means adapted to be operated by the rotation of the tools to automatically force said paste out through the foraminous faces of the tools, and means to 25 expand the tools simultaneously and equally as the grinding progresses.

13. An apparatus for grinding surfaces, comprising a hollow grinding tool formed with a foraminous grinding face and adapted to be filled with grinding paste, means to

cause relative grinding movement between the tool and the surface to be ground, means adapted to cause the said paste to be forcibly and positively and automatically fed through the foraminous face of the tool by 35 the said grinding movement, and means to render said paste feeding means inoperative by relieving the pressure on said paste.

14. In a grinding machine, a plurality of tool-driving shafts and means for simultaneously and synchronously rotating them, a tool-engaging member on each of said shafts, a plurality of cylindrical grinding-tools each composed of expansible sections for internal grinding, a shaft for each of 40 these grinding tools, means normally tending to draw said sections inwardly away from the work, means carried by the tool-shafts for expanding said sections when the tool-shafts are forced inwardly toward the 45 tool-engaging members, and means for simultaneously and synchronously forcing said tool-carrying shafts inwardly to thereby expand the grinding sections and also cause the tool to have driving connection with said 50 tool-driving members.

In testimony whereof I hereunto affix my signature.

JACOB LOWE YOUNG.
